UNITED STATES PATENT OFFICE.

GUSTAV EGLOFF AND HARRY P. BENNER, OF INDEPENDENCE, KANSAS, ASSIGNEES
TO UNIVERSAL OIL PRODUCTS COMPANY, OF CHICAGO, ILLINOIS, A CORPORATION
OF SOUTH DAKOTA.

HYDROCARBON-OIL TREATMENT.

No Drawing.

Application filed August 20, 1920. Serial No. 404,910.

To all whom it may concern:

Be it known that we, GUSTAV EGLOFF and HARRY P. BENNER, citizens of the United States, residing in the city of Independence, county of Montgomery, and State of Kansas, have invented certain new and useful Improvements in Hydrocarbon-Oil Treatment, of which the following is a specification.

10 Our invention relates to a process for the refining of hydrocarbon oils of the character resulting from the distillation of crude petroleum oils, pressure distillation, of heavy oils, shale, coal, peat and lignitic oils, or 15 the like.

The feature of novelty in our process lies in the treatment of hydrocarbon oils to produce sweet odored water-white light oils therefrom by means of an acid and a 20 comminuted solid material. Among the salient objects of our invention are, to provide a process for the production of water-white light oils; to provide a process for the refining of hydrocarbon oils; to produce sweet 25 odored, water-white gasoline and kerosene in one operation; to provide a process in which a minimum amount of acid is required comparative to the comminuted solid material; to provide a process in which a 30 liquid and a solid comminuted material are utilized to produce in the refining of hydrocarbon oils to produce marketable light oils therefrom; to provide a process in which an acid and comminuted solid material such 35

as fuller's earth is utilized to refine hydrocarbon oils to produce water-white, sweet odored light oils therefrom; to provide a process in which hydrochloric acid, or the like, and fuller's earth, or the like, are 40 placed in the body of a hydrocarbon liquid to be refined to water-white products. An illustrative test of process was to treat a cracked pressure distillate of 45 Baume gravity with a mixture of hydrochloric acid 45 and fuller's earth set within the body of the liquid and distilling therefrom to water-white, sweet odored gasoline and kerosene.

A still was charged with pressure distillate oil, fuller's earth and hydrochloric acid 50 and produced gasoline and kerosene of water-white, sweet odored, and having non-

resinous forming properties, unlike the usual cracked gasoline and kerosene which upon standing in the sun or other light source form resin-like bodies which have explosive 55 properties. The gasoline and kerosene produced by this process is stable as to color, odor and non-resin forming properties after standing in the sunlight for periods of time. The fact that this process gasoline and kero- 60 sene has no resinifying properties and color change properties is of importance commercially, for it is well known in the art that the resinifying properties, if not removed, gum up the carburetor of an automobile engine, causing annoyance and a non-sale of 65 the cracked gasoline. This obnoxious feature is overcome by this process.

As one method of carrying out our process, which is, however, only illustrative of 70 many others, we have successfully charged a container with 1,000 cc. of pressure distillate oil, with which I have mixed 500 cc. of fuller's earth and 50 cc. of hydrochloric acid. The specific oil which I used had a 75 Baume gravity of 45.0. The oil in the presence of the fuller's earth and hydrochloric acid was subjected to distillation. The oil treated had an initial boiling point of 122° F., with 90% thereof distilling at 530° F. 80 The color of the oil before distillation was a yellowish brown and in distilling the oil we selected, three hours and seven minutes was required, the distillation range of the oil being 408° F. 85

The distillation of the product resulted in the formation of 37½% thereof as gasoline, of a gravity of 58.4. This gasoline had an initial boiling point of 125° F., and an end point of 440° F. In 5% fractions, the 90 first 5% went over at 158° F., while the final fraction that was distilled, same being the 93rd per cent thereof, went over at 440°.

The kerosene fraction recovered was 29½% and of a gravity of 40.2. It had an 95 initial boiling point of 290° F., with an end point of 558° F.

In both the gasoline fraction and the kerosene fraction, the color both before and after distillation was water white.

We claim as our invention:

1. A process of refining cracked petroleum

oils consisting in distilling said oils while subjected to the action of hydrochloric acid and comminuted fuller's earth.

2. A process of refining cracked petroleum oils consisting in distilling said oils while subjected to the action of an acid and comminuted fuller's earth.

3. A step in the process of refining oils which comprises subjecting cracked petroleum oil while in the presence of hydrochloric acid and comminuted earthy material to a distillation temperature. 10

GUSTAV EGLOFF.
HARRY P. BENNER.
